ABSTRACT

A dual compartmented carton adapted to hold two or more items that might be of different size and shape wherein the carton contains an exposed tray-like upper portion for packaging one or more of the items completely visible to the consumer, and an enclosed lower portion for packaging the other items. The carton is constructed from a one-piece blank of material such as paperboard or the like so that the two portions are isolated from one another by a carton partition element or panel.

4 Claims, 4 Drawing Figures

MULTI-PRODUCT CARTON

This application is a division of the copending application Ser. No. 136,917, filed Apr. 23, 1971 now U.S. Pat. No. 3,724,650.

SUMMARY OF INVENTION

The present invention relates generally to a one-piece collapsible carton and is particularly concerned with a paperboard carton that is constructed and arranged to hold at least two separate items in separate compartments within the same package. The items may be the same or similar, or, may be of different kind, size and/or shape and still be accommodated by the carton construction anticipated.

From time to time it has been found desirable to package at least two items in a single carton so that they may be sold together. Such an arrangement is particularly useful where the seller desires to introduce a new product on the market and as a means of introduction gives a sample package of the new product to a customer purchasing an older or better known product. In many instances the two items are not exactly of the same shape or they are of different size. For example, certain types of washing powders or detergents have been sold in combination with a can of scouring powder or the like. Similarly it is not unusual to find multipaks of different womens cosmetics being sold on the shelf. As a result of these combination sales, the items are often difficult to support in a package in side-by-side relation, and it is difficult to retain both of the items in the same package. Accordingly, the present invention was devised to hold at least two items in separate compartments of the same package, and in the construction disclosed, the items may be of the same type, or of materially different size and shape, and at least one of the packaged items is preferably exposed for viewing by the consumer.

An object of the present invention resides in the provision of a simple paperboard carton comprising a tray-like upper portion and an enclosed lower portion in combination for retaining two items for sale which are readily handled and sold as a unit.

A feature of the carton described herein resides in the provision of a package which is extremely inexpensive to produce and which can be made on readily available equipment. Moreover, the carton of the present invention is capable of being filled and assembled either by hand or on high speed packaging machinery. In addition, the carton is capable of being shipped in a flattened or collapsed condition to minimize costs of handling and shipping a supply of the cartons to the packager.

A further object of the present invention is the feature whereby each compartment of the carton may be especially formed to receive a particular size and shape article with at least one of the articles being advantageously displayed.

Accordingly, it is a feature of this invention to provide an improved carton for packaging two or more related but dissimilar articles, as well as articles generally, wherein the container is provided with unique compartment and shelf means therewithin to support such items.

In at least one embodiment of the present invention the carton is designed to contain as a first item, a can or the like in the exposed upper tray-like portion of the

package with an enclosed space in the lower portion of the carton for housing the second item completely isolated from the first item. The outer or remote ends of the can or the like are held engaged in the carton or tray by means of tabs which enter the chime ends of the cans to hold these ends from removal. The tabs may be formed as a part of any one of the end closure flaps of the carton as shown in the drawings. Each tab is provided with arcuate edges which are designed to engage against the inner surface of the chime of the can to position the can firmly against the bottom of the upper tray. Once the collapsed carton is set-up for filling and the can or the like inserted in the upper end thereof, the can acts to hold the carton in the closed condition.

In other embodiments of the present invention, the package is designed to hold specific items of any desired shape in the upper tray-like portion of the carton by means of carefully shaped slots formed in the tab like elements attached to any one of the end closure flaps of the carton. Of course, in each of the embodiments discussed thus far, the lower portion of the carton remains completely enclosed for retaining the second item isolated with regard to the first item.

Other and distinct embodiments of this invention employ different means for closing the ends of the novel carton disclosed herein including different means for obtaining access to the enclosed lower portion of the carton. However, each and every embodiment of the invention disclosed herein retains the basic novel concept of providing a dual compartmented carton having an exposed tray-like upper portion with an enclosed lower portion wherein the two portions are isolated from one another by a carton partition element or panel.

These and other objects and novel features of the present invention will be more clearly and fully set forth in the following specification and claims.

DESCRIPTION OF DRAWINGS

FIG. 1 is a plan view of a flat paperboard blank from which one embodiment of the carton of this invention may be folded;

FIG. 2 is a perspective view on an enlarged scale of the partially folded carton constructed from the blank of FIG. 1.

FIG. 3 is a plan view of a flat paperboard blank from which a modified form of the carton of the present invention can be constructed; and,

FIG. 4 is a perspective view on an enlarged scale of the partially folded carton constructed from the blank of FIG. 3.

DETAILED DESCRIPTION

While the various features of this invention are hereinafter illustrated and described as being particularly adaptable for packaging at least two or more related but dissimilar articles including cans, as well as for packaging similar articles or the like in combination, it is to be understood that the various features of this invention can be utilized singly or in combination to provide cartons for other articles as desired. Accordingly, this invention is not to be limited to only the embodiments illustrated in the drawings because the drawings are merely utilized to illustrate examples of the wide variety of uses of this invention.

In the exemplary embodiments of the invention illustrated in FIGS. 1-4, an improved carton for packaging two or more articles is shown. Moreover, for this first embodiment of the present invention, the carton is illustrated as having a lower, enclosed compartment 3 and an upper, exposed tray-like compartment 5.

Referring now to the drawings in detail and particularly to FIG. 1, there is shown a flat blank of paperboard or the like which is cut and scored to form the container illustrated in FIG. 2. The paperboard is of a conventional type and may be coated one side or both, and/or printed as desired for the ultimate end use. As shown in FIG. 1, the blank includes a plurality of main panels 10, 12, 14 and 16 separated from one another by fold lines or the like. Panels 14, 12 and 16 also have attached to their respective ends along fold lines, pairs of end closure flaps 30, 26 and 28. Meanwhile, panel 14 also has attached along its respective sides the secondary panels 20. These latter panels 20 are shown as being attached to the main panels along suitable fold lines and may be referred to as adhesive panels since they ultimately are adhered to the respective main panels 12 and 16 in the final configuration. Moreover, the secondary panels 20 which form the inside walls of the double thickness sidewalls of the upper exposed tray-like compartment 5, give the upper edges thereof a finished surface along the fold lines 23 and 27 as shown in FIG. 2.

As shown in FIG. 2, the blank is folded and glued before being filled and closed either by hand or on properly programmed folding and gluing machinery. In most instances, the blanks are printed with the appropriate identifying matter and advertising information and then shipped to the user in a pre-glued flat form. The user then need only fill the carton before securing the end closure flaps.

The carton is filled by initially placing one of the articles to be packaged within the enclosed compartment 3 (FIG. 4) prior to folding the closure flaps 24, 26, 28 into closed condition. With the first item enclosed as described it is only necessary to insert the second article into the exposed tray-like compartment 5 as herein-after described.

The embodiment of the present invention illustrated in FIGS. 1 and 2 features a novel method for enclosing the lower enclosed compartment 3 after the product is stored therein. The blank is illustrated in FIG. 1 and it includes the usual panels 10, 12, 14 and 16 which form the bottom wall, a sidewall, the intermediate divider wall and a second sidewall, respectively, of the carton illustrated in FIG. 2. End closure flaps 26 and 28 are shown attached to the panels 12 and 16, and combination end closure flaps 30, 60 and a tuck closure flap 62 are shown attached to each end of the panel 14. The product retaining flaps 30 are each shown as having cut-outs 38 therein for accepting in a more-or-less fixed position the item packaged in the exposed compartment 5.

The carton blank is initially applied with adhesive along the inside faces of each of the secondary panels 20 and panel 14 is reverse folded along fold line 21 as the right panel 20 is folded about fold line 23 to be adhered to panel 12. Then panel 10 is folded about fold line 25 to expose the outside face of glue flap 18. Adhesive is next applied to flap 18 and panel 16 is folded about fold line 27 to adhere the inside face of panel 16 to both the left panel 20 and the glue flap 18. Accord-

ingly, the carton shown in FIG. 2 is obtained and need only then be set-up for filling and closing. Of course, for this embodiment, a single glue station could be used with both top and bottom glue pots for the application of adhesive to both panels 20 and glue flap 18.

The filling and closing of the carton of FIG. 2 is accomplished with a simple tuck style flap arrangement associated with the product retaining panels 30. The product retaining panels 30 assume an angular relationship to the carton divider wall 14 and break at the fold line 59 to provide the end walls 60 separated from the tuck flap 62 by the fold line 61. The product retaining cut-outs 38 in panels 30 are adapted to be tailored for the desired product to be displayed, and, the article stored in the enclosed compartment 3 is securely held in place in isolated relation to the article in compartment 5. As in the case of the other embodiments of this invention disclosed herein, the entire package would then preferably be wrapped for display and sale.

FIGS. 3 and 4 of the present invention disclose a modification of the carton disclosed herein which incorporates the best features of the invention as shown in FIGS. 1-2. That is, the carton disclosed in FIG. 4 is set-up and glued in substantially the same manner that the carton disclosed in FIG. 2 is set-up and glued, and, the carton of FIG. 4 can be loaded and closed substantially like the carton of FIG. 2. Of course, the reference characters used in FIGS. 3 and 4 designate similar elements in the blank structure disclosed in the other embodiment herein. Accordingly, the main panels 10, 12 and 16 still correspond to the bottom and two sidewalls of the carton while the panel 14 retains its identity as the carton intermediate dividing wall which separates the carton into two distinct compartments. Only one secondary panel 20 is shown as being attached between the main panels 14 and 16 with a closure or glue flap being attached to the free edge of panel 14. A secondary flap 40 is shown attached to the free edge of panel 12 and for this modification the secondary flap 40 is shaped like the integral secondary panel 20, but, in addition thereto, includes an extension that is the same size as the closure flap 18. Therefore, because of this added feature, the modification shown in FIG. 4 incorporates an improved runnability feature.

The carton of FIG. 4 is formed by pre-applying adhesive to the inside surfaces of panels 20 and 40 with a pair of top glue pots while simultaneously applying adhesive to the outside surface of closure flap 18 with a bottom glue pot. The blank is then folded into the desired configuration by initially folding secondary flap 40 into contact with the inside of panel 12 while simultaneously folding secondary panel 20 over into contact with the inside of panel 16 to expose the adhesive applied side of closure flap 18. Obviously these two folds could be made separately, but for the sake of efficiency they are preferably made simultaneously. These two folds, of course, yield a partially assembled carton blank which will have a tray-like upper portion with double thickness side walls and smooth upper edges. Finally, the construction is completed by folding the double thick side wall comprising panel 12 and secondary flap 40 over and into contact with exposed adhesive applied side of closure flap 18. Thereby, the glue flap 18 is adhered directly to the extension element of secondary flap 40 which was previously adhered to the panel 12. This scheme yields the desired improved runnability as described hereinbefore. Thus, the carton

structure of FIG. 4 is completed prior to being filled and closed.

For this latter function, it should be noted that the carton of FIG. 4, like the carton of FIG. 2, is susceptible to being loaded both top and bottom from the end with one end closure flap open for the purpose. A further feature of the cartons of both FIGS. 2 and 4 lies in the fact that the end panels 30 and 22 respectively may contain one or more openings for retaining therein one or more examples of the product exposed for view. The carton of FIG. 4 is moreover, especially useful for packaging fragile items since the partition panel 14 serves as a cushioning member between the product and the bottom of the carton. Furthermore, experience has shown that the displayed item when end loaded in the carton makes the carton more pilfer proof in the absence of an overwrap.

In the detailed description of the two embodiments of this invention, the different panels have been described as being folded in a particular manner to yield the carton structures illustrated. It should be apparent, however, to one skilled in the art, that other and different schemes could be advantageously used to achieve the same results as obtained herein. That is, a combination of the different features shown in the different embodiments could be interchanged for packaging specific articles within the scope of the invention as disclosed. In that connection, the terms, "bottom," "side walls" and "end flaps" and the like have been utilized in the description for the sake of continuity and to define the position of the respective elements as shown in the drawings. These definitions should by no means be considered limiting.

The different modifications and embodiments disclosed herein illustrate how the principles of this invention can be achieved in a variety of ways all within the scope of the invention as defined in the appended claims.

I claim:

1. A dual compartmented carton formed from paper-board or the like comprising:
a. a single blank of material scored to form a plurality of main panels separated from one another along

40

parallel fold lines and a carton closure flap connected to one of said main panels;

- b. said main panels including a bottom wall, a pair of sidewalls and an intermediate wall which divides the carton into an upper exposed tray-like compartment and a completely enclosed lower compartment, said sidewalls being common to both the completely enclosed lower compartment and the upper tray-like compartment, with the intermediate wall of the carton serving as both the top of the completely enclosed lower compartment and the bottom of the said tray-like upper compartment;
  - c. first and second end closure flaps integral with one another and connected to the intermediate wall of said carton for enclosing the ends of said lower compartment and said upper tray-like compartment, said first and second end closure flaps being angularly related to one another and to the intermediate wall of said carton;
  - d. said second end closure flaps forming finished upper edges for each end of said upper tray-like compartment at the point where said second end closure flaps are integrally joined to said first end closure flaps and including cutout means integral therewith for retaining one or more products securely located in the upper tray-like compartment; and,
  - e. a pair of secondary panels connected along fold lines to one of said main panels to form both sidewalls of said upper tray-like compartment of double thick material with finished upper edges.
2. The carton of claim 1 wherein the secondary panels are connected to each side of said intermediate panel.
3. The carton of claim 1 wherein the secondary panels are connected to the edges of said sidewall panels.

4. The carton of claim 3 wherein one of said secondary panels includes an extension which overlaps the carton closure flap connected to one of said main panels.
